FENDER ORNAMENT FOR AN AUTOMOBILE

David E. Scott, Detroit, Mich., assignor to Chrysler Corporation, Highland Park, Mich., a corporation of Delaware

Application March 18, 1950, Serial No. 8,633

Term of patent 7 years

(Cl. D14—6)

To all whom it may concern:

Be it known that I, David E. Scott, a citizen of the United States, residing in the city of Detroit, county of Wayne, and State of Michigan, have invented a new, original, and ornamental Design for a Fender Ornament For An Automobile, of which the following is a specification, reference being had to the accompanying drawing, forming part thereof, in which:

Fig. 1 is a front elevational view of a fender ornament for an automobile, showing my new design;

Fig. 2 is a side elevational view thereof;

Figs. 3 and 4 are cross sectional views taken on the lines 3—3 and 4—4 respectively of Fig. 1; and

Fig. 5 is a front elevational view of the fender ornament for an automobile of my invention, the

broken lines showing therein of a portion of the automobile being for illustrative purposes only.

The characteristic features of my design reside in the portions shown by means of full lines in the drawing.

I claim:

The ornamental design for a fender ornament for an automobile, substantially as shown and described.

DAVID E. SCOTT.
